Specification for Design.

Patented Aug. 27, 1918.

Application filed August 2, 1917. Serial No. 184,159. Term of patent 14 years.

To all whom it may concern:

Be it known that I, EDWARD H. BELDEN, a citizen of the United States, residing at Toledo, in the county of Lucas and State of Ohio, have invented a new, original, and ornamental Design for an Automobile-Lamp Casing, of which the following is a specification, reference being had to the accompanying drawing, forming a part thereof.

Figure I is a view in front elevation of

an automobile lamp casing showing my new design.

Fig. II is a view in side elevation of the lamp casing shown in Fig. I.

I claim the ornamental design for an automobile lamp casing as shown.

In testimony whereof, I affix my signature.

EDWARD H. BELDEN.
